UNITED STATES PATENT OFFICE

FRANK J. ABEL, OF MASSAPEQUA, NEW YORK, ASSIGNOR TO HENRY HYMAN, OF BROOKLYN, NEW YORK

DESIGN FOR A COMBINED FIGURE AND RECEPTACLE

Application filed May 5, 1933. Serial No. 48,019. Term of patent 7 years.

To all whom it may concern:

Be it known that I, FRANK J. ABEL, a citizen of Germany, residing at Massapequa, county of Nassau, and State of New York, have invented a new, original, and ornamental Design for a Combined Figure and Receptacle, of which the following is a specification, reference being had to the accompanying drawing, forming a part thereof, in which Fig. 1 is a front view of a combined figure and receptacle showing my new design and Fig. 2 is a side view of the same.

I claim:

The ornamental design for a combined figure and receptacle, as shown.

FRANK J. ABEL.
